(57) **CLAIM**

The ornamental design for a burger press, as shown and described.

DESCRIPTION

FIG. 1 is a front, exploded perspective of the burger press showing my new design;

FIG. 2 is a front, exploded elevational view thereof;

FIG. 3 is a rear, exploded elevational view thereof;

FIG. 4 is a right side, exploded elevational view thereof;

FIG. 5 is a left side, exploded elevational view thereof;

FIG. 6 is an exploded top plan view thereof; and

FIG. 7 is an exploded bottom plan view thereof; and,

FIG. 8 is a front perspective view of the burger press, with each component thereof in an assembled configuration as would be seen during the intended use thereof.

1 Claim, 6 Drawing Sheets**FIG. 1**

FIG. 2**FIG. 3**

FIG. 4**FIG. 5**
